MULTIPLE SEATING UNIT

Eliot Noyes, New Canaan, and Ernest M. Bevilacqua,
Wilton, Conn., assignors to Eliot Noyes & Associates,
New Canaan, Conn.

Filed Dec. 2, 1971, Ser. No. 204,402

Term of patent 14 years

Int. Cl. D6—01

U.S. Cl. D6—59

Fig. 1.

Fig. 2.

FIG. 3.FIG. 4.

FIG. 1 is a perspective view of a multiple seating unit showing my new design.

FIG. 2 is a bottom plan view thereof.

FIG. 3 is an enlarged fragmentary perspective view of a single seat thereof, with the remaining seats being omitted; and

FIG. 4 is an enlarged fragmentary end elevational view of a single seat thereof, with the remaining seats being omitted.

We claim:

The ornamental design for multiple seating unit, as shown.
